BLASTING MACHINE

Morris E. Reed, Berkeley, Mo., assignor to Universal Match Corporation, St. Louis, Mo., a corporation of Delaware

Filed Mar. 30, 1964, Ser. No. 79,254

Term of patent 14 years

(Cl. D55—1)

FIG. 1.

FIG. 2.

FIG. 3.

FIG. 4.

FIG. 1 is a plan view of a blasting machine embodying my design,

FIG. 2 is a side elevational view of the blasting machine of FIG. 1,

FIG. 3 is an end elevational view of the blasting machine of FIG. 1, and

FIG. 4 is a bottom view of the blasting machine of FIG. 1.

I claim:

The ornamental design for a blasting machine, as shown and described.
